FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

THREAD-CONTROLLING MECHANISM FOR SEWING-MACHINES.

1,183,394.

Specification of Letters Patent.

Patented May 16, 1916.

Application filed September 19, 1910. Serial No. 582,599.

To all whom it may concern:

Be it known that I, FRANK W. MERRICK, a citizen of the United States, residing at Boston, in the county of Suffolk, State of 5 Massachusetts, have invented a certain new and useful Improvement in Thread-Controlling Mechanisms for Sewing-Machines, of which the following is a specification, reference being had therein to the accompanying drawings.

The invention has relation to the devices which are employed in sewing machines for controlling the thread which is supplied to the needle.

15 The invention combines with a take-up for the thread which is supplied to the needle, and an intermittent thread-lock operating to lock the thread at the supply-side of the take-up against the pull of the latter 20 at the time of each taking-up action and at other times leaving the thread unlocked, means adapted to be brought into operation by the operator to prevent the locking of the thread while a taking-up action occurs, 25 as for instance in starting the machine.

The purpose is to enable the action of the thread-lock in intermittently locking the thread to be temporarily suspended, so that, in practice, the material to be stitched having been inserted between the work-support and presser while the machine is standing at rest, on starting the machine the thread will not be locked at the supply-side of the take-up at the time of the first taking-up 30 operation. The result of preventing the thread-locking action at this time is, assuming the leading end of the thread to be held either in the operator's hand or by being clamped under presser, that the take-up device in the said first operation thereof will pull forward from the supply-side thereof the full amount of thread that may be needed for the operations in forming the first stitch. This obviates the necessity of 35 drawing forward by hand from the source of supply, prior to starting up, a considerable amount of thread so as to provide at the work side of the take-up a leading end of length great enough for the said operations, and intended to be drawn backward by the first taking-up action. Heretofore much waste of thread has occurred because an excess of thread usually has been drawn forward in starting up, such excess being afterward cut off and thrown

aside. With this feature of my invention in use, it is necessary to draw forward by hand at the outset only sufficient thread to furnish a free end to hold in one's hand or to clamp under the presser. Thereby the waste referred to is obviated. In carrying the invention into effect, the means for preventing the locking of the thread is most advantageously combined with the means for lifting the presser of the machine, 60 so that at the same time that the presser is raised in readiness to receive between it and the work-support the material to be stitched the lock-preventing means is rendered operative. With the lock-preventing means I combine means operated by a moving part of the machine, whereby the lock-preventing means is automatically rendered inoperative, after the first taking-up action has taken place. I usually employ a 65 thread-lock of the type actuated by the thread itself in being taken up, and usually termed in the art a thread-grip, and combine the lock-preventer therewith in such manner that when the lock-preventer is 70 rendered operative it prevents the pull of the thread under the taking-up action from closing the thread-lock upon the thread, thereby attaining the desired end of 75 leaving the thread capable of rendering past 80 the thread-lock as the take-up acts.

An embodiment of the various features of the invention is illustrated in the accompanying drawings, in which latter,—

Figure 1 shows in side elevation certain of the parts of a curved needle sewing machine having the said embodiment applied in connection therewith, the take-up arm being partly broken away to show the lock-preventer more clearly. Fig. 2 shows some of the said parts in plan. Fig. 3 shows in side elevation on a somewhat smaller scale some of the parts of a machine of the same order as that of Figs. 1 and 2, representing more particularly the presser-mechanism and the 85 needle-and-awl mechanism.

Having reference to the drawings,—the machine-frame is marked 1, and 2 is the main or driving shaft. At 3 is the work-support, and 4 is the presser between which 90 and the work-support the work *a* to be stitched is placed. I will give a brief preliminary description of the presser-mechanism, and of the needle-and-awl mechanism, and then describe the parts more im- 95 100 105 110

mediately involved in the invention and explain the embodiment of the different improvements.

The presser-carrier is shown at 5, Fig. 3, chiefly in dotted lines, the pivotal support of the presser-carrier being marked 6. Fig. 3 shows a convenient means of applying spring-tension to the presser-carrier to cause the presser to hold the material *a* firmly against the work-support. The presser-carrier is furnished with a downwardly-extending arm 7, with which is connected pivotally a rod 9 that passes through an opening in a small upright stand 10 rising from the bed of the machine-frame 1. The said rod is encircled at the rear of the said stand by an expanding spiral spring 11, the latter being confined between the stand and a loose collar 12 upon the rod, the said loose collar being backed up by an adjustable nut 13 on a screw-threaded portion of the rod, the adjusting nut 13 being backed up by a lock-nut 14. The expansive force of the spring is transmitted through the rod to the arm 7 of the presser-carrier, and acts with a tendency to turn the presser-carrier 5 so as to cause the presser to approach the work-support.

15 is a curved awl, and 16 the awl-carrier segment, 17 being a curved hook-needle and 18 the needle-carrier segment. The two carrier-segments are mounted to turn around a common center, and are connected to swing in unison by means of a pin 19 (shown by dotted lines) carried by one carrier-segment and passing transversely through a hole in the other carrier-segment. They are actuated from the main or driving shaft 2 by means of an arm 20 projecting from one carrier-segment, a link 21 having one end thereof connected pivotally to said arm, a walking-beam lever or rocker 22, (Fig. 3) having the other end of link 21 connected pivotally with its forwardly-projecting arm, and a link 23 having one end thereof connected pivotally with the rearwardly-projecting arm of the said walking-beam lever or rocker and the other end thereof engaged with a crank 24 on shaft 2. The walking-beam lever or rocker 22 is constructed with a rockshaft 22^a which is mounted in bearings in the head-portion of machine-frame 1. As the shaft 2 rotates, motion is transmitted from the crank through the described connections to the two carrier-segments, oscillating the latter and the awl and needle mounted thereon.

Referring, now, to the thread-guide by which the thread is laid around the needle and into the open eye of the latter, it is shown at 25, Figs. 1 and 2. It is secured to a carrier-lever 26. I construct the said carrier-lever with an open hub-portion, shown best in Fig. 1, which encircles loosely a collar 27 that is sleeved loosely upon the trans-

versely-extending horizontal rockshaft 22^a of the walking-beam lever or rocker 22. The said hub-portion is swiveled to the said collar by means of upper and lower center-screws 28, 28. As thus mounted, the thread-guide carrier-lever is capable of swinging transversely in the direction of the length of the rockshaft upon its pivotal connection with the collar, while in addition the carrier-lever and collar are capable of oscillating around the rockshaft. For the actuation of the carrier-lever and thread-guide a cam 29 is fixed upon the shaft 2, such cam having a cam-groove receiving a cam-follower 26^a which is connected with the rear arm of the carrier-lever. The said cam has both radial throws acting to oscillate the carrier-lever and thread-guide vertically, and lateral throws acting to swing the carrier-lever and thread-guide transversely, so as thereby to cause the thread-guide to travel in the required path to lay the thread in the eye of the needle. In practice, a spring, 26^b, acts upon carrier-lever 26 with a tendency to press the cam-follower 26^a toward the bottom of the cam-groove.

At 30 is the thread-finger or thread-hook by means of which the length of thread to be drawn through material *a* by the needle in the descent of the needle is extended in a bend or bight. It is secured to a carrier-lever 31 which is mounted upon rockshaft 22^a alongside the collar 27 with capacity to turn loosely on the said rockshaft, and is actuated by means of an edge-cam 32 on shaft 2, which engages with a cam-follower 31^a carried by the rear arm of the carrier-lever 31. In practice, a spring, 31^b, acts upon the carrier-lever 31 with a tendency to press the cam-follower 31^a against the edge of the cam 32.

The employment of the rockshaft 22^a of the actuating rocker or walking-beam lever of the needle-and-awl mechanism as a support for the carrier-levers of the thread-guide and thread-finger or thread-hook provides effectively for the secure mounting of the said carrier-levers in the proper relative positions with respect to the other working parts to obtain advantageously the co-operation of the thread-guide and thread-finger or thread-hook with the needle, slack-thread controller, and take-up, and dispenses with separate studs or pivots. The general construction of the machine is simplified and improved, and durability and freedom from wear and breakages are secured.

Reference will now be made to the taking-up and locking devices for the needle-thread. The latter as it extends from the source of supply passes down into the wax-pot 33, then up to and through a tension-device 34, then to the locking device, then to the take-up, and thence past a slack-thread con-

troller and through the thread-guide 25 to the work *a*.

The take-up may be, in practice, of any approved and suitable construction. The 5 drawings show a convenient form thereof which consists of a vibrating arm 35 carrying two thread-engaging rolls 36, 36, and a cooperating thread-engaging roll 37 which is mounted on a pivot 38 upon the head- 10 portion of the machine-frame 1, the said roll 37 engaging with the thread at a point intermediate the points at which the two rolls 36, 36, engage therewith. The arm 35 is fixed upon one end of a rockshaft 39 ex- 15 tending through a sleeve bearing 40 in connection with the said head-portion of the machine-frame, as shown best in Fig. 2. The said rockshaft has fixed upon its other end a second arm, marked 41, carrying a 20 cam-follower 42 working in the cam-groove 43 of a cam-wheel 44 fixed on shaft 2. As the said cam-wheel rotates, it communicates a vibrating movement to the take-up arm, as a result of which the rolls 36, 36, on said 25 arm cooperate with the fixedly mounted roll 37, and with the grip-device, to draw out the thread in extended bends or bights at opposite sides of the roll 37, thereby taking up the thread between the grip-device and the 30 work in completing each stitch as it is formed. A special feature in the illustrated construction of take-up is the comparatively long bearing-support for the rockshaft 39 between the power-receiving arm 41 and the 35 take-up arm 35. The said rockshaft is supported close up to each of the said arms, thereby preventing springing of the rock- shaft in operation, while the length of the bearing support obviates all tendency of the 40 rockshaft to bind in the bearing. The rock- shaft is formed adjacent the power-receiving arm 41 with a cone 39^a which fits a tapering enlargement of the bore of the sleeve bearing 40 at the corresponding end of the latter. 45 The hub of the arm is sleeved upon the other end of the rockshaft and provided with the cone 39^b fitting within a tapering enlargement of the bore of the sleeve bearing at the corresponding end of the sleeve bearing. 50 To prevent the arm 35 from turning relative to the rockshaft, the latter is flattened transversely, and a clamping-screw arrangement (not shown) applied to the hub-portion of the arm takes against the flattened 55 surface of the rockshaft. The latter end of the rockshaft is screw-threaded and the nut and lock-nut 39^c screw thereon. This construction enables the nuts 39^c to be screwed up so as to cause both cones to fit snugly 60 within their tapering seats in the opposite ends of the sleeve bearing, and renders it possible to take up all wear. Thereby looseness and play of the take-up device with reference to its support, and uncertainty 65 and variation in the action of the take-up

device, are avoided, and entire accuracy in such action is secured.

The slack-thread controller is located between the take-up device and the thread-guide. It comprises a fixed plate or rest 45 70 for the thread, and a movable plate or pressure-member 46 carried by a lever 47 which is pivoted at 48 to the fixed head-portion of the machine-frame, the said lever having engaged therewith one end of a contracting 75 spiral spring 49 having the other end thereof connected with the said head-portion. The thread passes between the pressure-member 46 and the rest or backing 45, and is subjected to pressure between them, due to the 80 action of the spring 49 in tending to turn the lever 47. The slack-thread controller is so disposed that the portion of thread passing therethrough draws in nearly a straight line between the adjacent roll 36 of the take- 85 up and the thread-passage of the thread-guide 25. It acts to hold back the portion of thread which is slackened by the giving-up action of the take-up, after the taking-up action has occurred, but permits the 90 thread to pass forward under sufficient control to the stitch-forming devices as needed in the formation of a new stitch.

Various forms of thread-lock suitable for the purposes of my invention are known in 95 the art, and may be employed as preferred. I have shown a form of well-known type, the same comprising a lever 50 and a bearing or rest 51 for the thread. The said lever is pivoted at 52 upon the head-portion of 100 the machine-frame adjacent the take-up arm, and in such relation to the latter that the thread on its way from the tension device 34 engages with the lever before reaching the first of the moving take-up rolls 36. The 105 lever 50 is furnished with a laterally-extending thread-gripping stud or projection 50^a, which is carried by one arm of the lever adjacent the pivot of the latter, the said stud or projection being arranged to co-act with the backing or rest 51 in gripping the thread at the required times. The said backing or rest is constituted by a fixed stud or projection carried by the support of the 110 grip-lever. The thread passes between the 115 backing or rest and the stud or projection 50^a of the lever. The long arm of the lever has at its forward end a guide which engages with the thread intermediate the gripping surfaces and the first roll 36 of the 120 take-up device, the said guide being at a somewhat greater distance from the pivot of the lever than the gripping stud or projection 50^a. When the taking-up action of the take-up device begins, the pull of the 125 thread upon this arm of the lever acts with sufficient leverage and force to turn the lever around its pivotal center so as to pinch the thread by means of stud or projection 50^a against backing or rest 51. When the pull 130

of the take-up upon the thread relaxes, the pressure of the said stud or projection is also relaxed, and the grip upon the thread ceases. The action in this respect is as usual.

The lock-preventer which I employ in carrying into effect that portion of the invention which involves the same may be of any approved character and construction suitable for the purpose. I have shown a form thereof in which is embodied certain specific features of the invention, and which I prefer. This form comprises an eccentric-piece 53 which is fixed upon a short rock-shaft 54, the latter being journaled in a bearing in the fixed head-portion of the machine-frame, adjacent the grip-lever. In one position, a portion of short radius of the said eccentric-piece is presented toward the long arm of the grip-lever, and as when this is the case the grip-lever is permitted to move so as to grip the thread as described above, the gripping action takes place at the time of each taking-up action. This is the normal position of the eccentric-piece, and is retained by it during the continuous working of the machine. In a second position of the eccentric-piece a portion thereof of longer radius is presented toward the grip-lever, this portion acting to prevent the grip-lever from moving under the pull of the thread thereon, at the time of the taking-up action, far enough to grip the thread. The eccentric-piece is shown in this position in Fig. 1 of the drawings, with the long arm of the grip-lever resting against the eccentric-piece and the grip-lever being prevented from pinching the thread between the stud or projection 50^a and the backing or rest 51.

For the purpose of enabling the lock-preventing member 53 to be called into action manually, its rockshaft 54 has fixed thereon a finger 55, Fig. 1, and an actuating lever 56 is pivoted at 56^a to the head-portion of the machine-frame, one arm of the said lever extending under the said finger. By turning the said lever so as to raise the said arm it is caused to engage with the finger 55 and turn the member 53 from its normal idle position into its working position shown in Fig. 1 for engagement with the grip-lever. Normally, the said arm of the actuating lever is depressed slightly from its position in Fig. 1, so as to permit the member 53 to assume and retain its normal position which allows the grip-lever to act in gripping the thread. For convenient actuation of the actuating-lever at the same time that the presser 4 is raised manually, the other arm of the actuating lever is connected, in the present instance, by a rod 57 with the foot-treadle 58 for use in raising the presser. For presser-raising purposes, the said treadle has connected therewith a

rod 59, the upper end of which connects with a horizontally-extending arm 60 of a bell-crank, the upwardly-extending arm 61 of which extends up at the rear of a collar 62 on a cylindrical piece 63 which is mounted on the rear end of rod 9. The said piece 63 has a threaded hole tapped in one end thereof and is screwed upon the said rear end. When the treadle is depressed, bell-crank 60, 61, is rocked and in the forward movement of its arm 61 the latter engages the collar 62, pushing rod 9 forward against the resistance of spring 11 and rocking the presser-carrier so as to separate the presser from the work-support. The character and construction of the connections for raising the presser and calling the lock-preventing member into action may be varied as desired in practice.

For the automatic return of the lock-preventing member 53 to its normal position in which the grip-lever is permitted to act, the rockshaft 54 of the said member is furnished with a second projecting finger, marked 64 in Fig. 1, and upon the rock-shaft 22^a a finger 65 for coaction with finger 64 is fixed. While the member 53 occupies its normal position, the finger 64 thereof is depressed below the path of the finger 65. The turning of the member 53 into its working position places the finger 64 in the position occupied by it in Fig. 1, which is within such path. The machine having stopped with the various parts in the positions occupied by them in Fig. 1, or in substantially those positions, with the member 53 in position for engagement with the grip-lever, the said member remains in such position, preventing the grip-device from closing upon the thread. This leaves the thread capable of rendering through the grip-device. Prior to restarting the machine, the leading end of the thread is placed beneath the presser and the latter is permitted to descend upon such end, or the end is held in the hand of the operator. The walking-beam lever or rocker 22 moves first in the direction to cause the awl 15 to enter the material *a*, and in so moving it carries the finger 65 upward away from the finger 64. A taking-up movement of the take-up arm also occurs, during which the grip-device is prevented by the member 53 from holding the thread, and the thread renders from the source of supply to the extent called for by the taking-up action. Following the movements just described, the walking-beam or rocker, rocks reversely to withdraw the awl from the material and cause the needle to enter the awl-hole made in the material, the take-up arm also moving reversely, and by this reverse rocking movement of the walking-beam lever or rocker the finger 65 is carried against the finger 64. Through this engagement of the

moving finger 65 with the finger 64 the eccentric member 53 is turned from its position in Fig. 1 to a position which releases the grip-lever for the control of the thread.

5 When the next taking-up action takes place the grip-lever is actuated by the thread to grip the latter between the take-up and the source of supply.

In practice, means will ordinarily be provided to relieve the pressure of the presser upon the work *a* at the time of the feed. An automatic device acting to lift the presser at such time will usually be employed.

15 I claim as my invention:—

1. In combination, a take-up for the thread which is supplied to the needle, an intermittent thread-operated thread-lock operating to lock the thread positively at 20 the supply-side of the take-up against the pull of the latter at the time of each taking-up action, and at other times leaving the thread unlocked, a continuously acting tension-device at the supply side of said thread-lock, and means adapted to be brought into 25 operation by the operator to suspend the locking of the thread while a taking-up action occurs.

2. In combination, a take-up for the 30 thread which is supplied to the needle, an intermittent thread-operated thread-lock operating to lock the thread positively at the supply-side of the take-up against the pull of the latter at the time of each taking-up action, and at other times leaving the thread unlocked, means adapted to be brought into operation by the operator to suspend the locking of the thread while a taking-up action occurs, a continuously acting 35 tension-device at the supply side of said thread-lock, and means operating to automatically render the lock-suspending means inoperative after such taking-up action has occurred.

45 3. In combination, a take-up for the thread which is supplied to the needle, an intermittently operating thread-operated thread-lock by which the thread is locked against the pull of the take-up at the time 50 of each taking-up action and at other times left unlocked, and means to suspend the locking of the thread in starting the machine until after the first taking-up action has occurred.

55 4. In combination, a take-up, an intermittent thread-operated thread-grip operating to hold the thread at the time of each taking-up action, and a grip-preventer adapted to be brought into operation to prevent the 60 gripping of the thread while an operation of the take-up occurs.

5. In combination, a take-up, an intermittent thread-operated thread-grip operating to hold the thread at the time of each taking-up 65 action, a grip-preventer adapted to be

brought into operation to prevent the gripping of the thread while a taking-up operation occurs, and means for automatically rendering the grip-preventer inoperative after the take-up has acted.

70 6. In combination, a take-up, an intermittently-operating thread-operated thread-grip operating to hold the thread at the time of each taking-up action and at other times leaving the thread free to advance, and 75 means by which the operator may render the thread-grip inoperative to hold the thread while a taking-up action occurs.

7. In combination, a take-up, an intermittently-operating thread-operated thread-grip operating to hold the thread at the time of each taking-up action and at other times leaving the thread free to advance, means by which the operator may render the thread-grip inoperative to hold the thread 85 while a taking-up action occurs, and means by which the thread-grip automatically is restored to operativeness after such action has occurred.

8. In combination, a take-up, a thread-operated thread-grip normally acting to lock the thread during each taking-up action and at other times leaving the thread free to advance, a grip-controller adapted to be set by the operator to prevent the thread-grip from 95 acting, and means for automatically actuating the grip-controller to restore the thread-grip to operativeness after the first taking-up action subsequent to starting the machine has occurred.

9. In combination a take-up, an intermittent thread-operated thread-grip normally acting to lock the thread during each taking-up action, and means to render the thread-grip inoperative in starting the machine 105 until after the first taking-up action has occurred.

10. In a sewing machine, the combination with a take-up, and a thread-grip actuated by the thread itself in being taken up, of a 110 grip-controller adapted to be controlled manually to prevent the pull of the thread from closing the thread-grip upon the thread, whereby the thread is left capable of rendering past the thread-grip as the take-up acts.

11. In a sewing machine, the combination with a take-up, a thread-grip actuated by the thread itself in being taken up, a grip-controller, a presser, and means whereby the 120 operator in raising the presser places the grip-controller in operative relations so that in the next taking-up operation the thread will render past the thread-grip.

12. In combination, a take-up, a thread-grip actuated by the thread itself in being taken up, a grip-controller to prevent the thread-grip from acting while a taking-up movement of the take-up occurs, and means to automatically render the grip-controller 125 130

inoperative and restore the thread-grip to operativeness after such taking-up movement has occurred.

13. In combination, a take-up, a thread-grip having a movable gripping member actuated by the thread itself in being taken up, and an eccentric grip-control member which in its normal position permits movement of said gripping-member and the gripping of the thread, and movable under control of the operator into another position in which it prevents such movement and prevents the gripping action during a taking-up action.

14. In combination, a take-up, a thread-grip having a movable gripping-member actuated by the thread itself in being taken up, an eccentric grip-control member which in its normal position permits movement of

20 said gripping-member and the gripping of the thread, and movable under control of the operator into another position in which it prevents such movement and the gripping

action, and means for returning said eccentric member to normal position when a 25 taking-up movement has occurred and thereby rendering the thread-grip operative.

15. In combination, a take-up, a thread-grip having a lever actuated by the thread itself in being taken up, an eccentric member which in its normal position permits movement of said lever by the thread and the gripping of the latter when the take-up acts, means through which the operator may cause such eccentric member to assume a 30 35 position which prevents the gripping of the thread, and a moving part of the machine which automatically returns the eccentric member to its normal position after a taking-up action has occurred.

In testimony whereof I affix my signature in presence of two witnesses.

FRANK W. MERRICK.
